EMILE BOURDELLES, OF PARIS, FRANCE, ASSIGNOR OF ONE-HALF TO COMPAGNIE DES FORGES ET ACIÉRIES DE LA MARINE ET D'HOMÉCOURT, OF PARIS, FRANCE, A JOINT-STOCK COMPANY.

ELEVATION-CONTROLLED FIRING APPARATUS FOR GUNS.

1,098,612.

Specification of Letters Patent.

Patented June 2, 1914.

Application filed September 27, 1913. Serial No. 792,224.

To all whom it may concern:

Be it known that I, EMILE BOURDELLES, a citizen of the Republic of France, resident of 39 Rue Galilée, Paris, France, have invented a new and useful Elevation-Controlled Firing Apparatus for Guns, which is fully set forth in the following specification.

In the devices described in my concurrent application Serial No. 791,972, filed September 26, 1913, for elevation-controlled firing apparatus for guns it may happen that the marksman fires the gun accidentally, if, before bringing it to his shoulder, he presses the trigger and at the same time imparts abnormal shocks to the gun. In this case, as operation has been prepared for by the action of the finger upon the trigger, the inertia of the gravity mass (even if the latter is reduced to a ball or a drop of mercury) may produce premature electrical contact if the gun is subjected to the shocks. In order to obviate this defect, in accordance with the present invention, a circuit breaker or cut-out acting by inertia is interposed in the electric circuit which actuates the trigger or the firing mechanism. This cut-out only renders inoperative the effects of a sudden longitudinal movement and allows perfect liberty for the establishment of the circuit when the gun moves in elevation. As hereinafter explained, this cut-out instead of being combined in series with the normal circuit breaker, might replace the latter, that is to say serve as the circuit-making element in the case of regular normal manipulation and also as a circuit breaker in case of irregular or abnormal manipulation.

Figure 1 of the accompanying drawing illustrates an embodiment of the invention in which the safety cut-out is employed in combination with the normal circuit breaker described in the principal patent. Fig. 2 is a longitudinal sectional elevational view of a second constructional form of my invention; Fig. 3 is a diagrammatic view illustrating a third constructional form; and Fig. 4 is a vertical sectional view of a gun showing my improvement in position.

In Figs. 1 and 4 *z* designates the base or

support upon which the normal device for making the circuit by means of a gravity member is mounted, such, for example as the device represented in Fig. 6 of the aforesaid specification. This device is constituted by a level *c* with a mercury drop *C*; the casing of this level consists of two cylindrical steel parts 1 and 2 separated by a cylindrical portion 3, of fiber or ebonite, fixed to the support *z* by a collar 4 or any other appropriate member. One of the parts of the casing (the part 2) is connected by the conductor *D'* with one of the elements of the circuit to be established, the other part 1 of the casing is connected by the wire *D* with the interposed safety cut-out, and the circuit can only be closed by the intermediary of the latter, which is connected by the conductor *D* with the other element of the circuit.

The safety cut-out can be constituted in the following manner:—A connection of insulating material 9 provided with a partition 10, a portion of which is rendered electrically conducting by means of a metallic bead 11, unites two closed metal tubes 12, 13 each of which contains a metal ball or a drop of mercury 14, 15. These two tubes 12, 13 are slightly inclined one toward the other.

In Fig. 4 I have shown a breech-loading gun provided with electro-magnetic means for firing the gun when any desired elevation is reached, the electromagnetic means being controlled by my safety cut-out. Only so much of the gun firing mechanism will be here described as is necessary to explain its connection with the present improvement as the same forms the subject-matter of my co-pending application Serial No. 791,972, filed September 26, 1913, wherein the same is fully described and claimed. *A* is the stock of a breech-loading gun in which is located a battery *a* and an electromagnet *b* which is in circuit with battery *a* and leads *D*, *D'* of the cut-out device and the trigger actuating device designated as a whole by *B*, the specific construction of which forms no part of the present invention and is not herein further described. *h* is a false trig-

ger which is adapted to act on the trigger proper *u* through a spring *j* to move a rod *g* carrying a contact piece *f* which may close a circuit through the electromagnet *b* preparatory to firing. A stop *i* limits the rearward movement of the false trigger and prevents firing by a pull on the trigger by the finger alone.

After the marksman has prepared the gun 10 by pressing the false trigger *h*, he elevates the gun progressively; when the gun passes through the given firing elevation the drop *C* forms a bridge between the two parts 1 and 2 of the level *c*, while the two drops 14, 15 of the safety cut-out permit of the establishment of the circuit by making contact with the metal bead 11. If on the other hand the marksman while pressing the trigger subjects the gun to sudden and inopportune movements one or other of the drops of mercury 14, 15 will cease to rest against the partition 10-11 and the circuit cannot be inopportunely formed.

If desired partial partitions 21 or other suitable baffles can be provided in the chambers 12, 13 to prevent any splashing or sudden return of the drops of mercury that the shock may have projected against the ends of the tubes.

30 In certain cases, the normal circuit making element can be dispensed with, that is to say, in the example illustrated in Fig. 1, the element *C* can be omitted and only the safety cut-out may be placed in circuit by 35 the wires *D*² and *D*.

Fig. 2 illustrates a second constructional form of the safety cut-out in longitudinal form of the safety cut-out in longitudinal sectional elevation. In an insulating tube 16 comprising stops or a circular projection 40 17, two conducting masses 14, 15 are displaceable; springs 18, 19 press these masses together and away from the extreme conducting plugs of the tube and tend to maintain them in contact. Any inopportune 45 movement given to the gun, separates the masses 14 and 15 and breaks the circuit. Instead of guiding the masses 14 and 15 in an insulating envelop, they might be guided upon an insulating axial rod comprising 50 stops.

Fig. 3 illustrates a third constructional form of the safety cut-out. In this example, two pendulous conducting masses 14 and 15 are normally maintained lightly in contact in such a manner as to enable the circuit to be made during the regular movements of the gun. With this object, the masses can be suspended on rigid rods making a slight angle one with the other, owing 60 to the suitable spacing of their points of suspension. An insulating stop 20 is interposed between the two masses. The suspension rods can be flexible to assist the return movement of the masses. Any sudden in-

opportune movement separates the masses 65 and breaks the circuit.

What I claim and desire to secure by Letters Patent of the United States is:

1. A circuit-controlling device for electromagnetically actuated firing mechanism for guns comprising circuit-closing means operable to close a circuit at one point when the gun is placed at a predetermined angle, and a circuit make and break device in circuit with said means and operable to break 75 the circuit at another point under the influence of a sudden jar to the gun and operable to close the circuit when the gun moves regularly in elevation.

2. A circuit-controlling device for electromagnetically actuated firing mechanism for guns comprising circuit-closing means operable to close a circuit at one point when the gun is placed at a predetermined angle, and means comprising two electrically conducting gravity actuated masses adapted to open the circuit at another point under the influence of an irregular movement of the gun in elevation and to close the circuit at this point when the gun moves regularly in elevation.

3. A circuit-controlling device for electromagnetically actuated firing mechanism for guns comprising circuit-closing means operable to close a circuit at one point when the gun is placed at a predetermined angle, and a circuit make and break device comprising two contact members and means supporting the same in operative relation to each other, both of said members being movable and 100 normally tending to close the energizing circuit of the firing mechanism when the gun is moved in elevation and to open the circuit when the gun moves irregularly in elevation.

4. A circuit-controlling device for electromagnetically actuated firing mechanism for guns comprising circuit-closing means operable to close a circuit at one point when the gun is placed at a predetermined angle, and a circuit make and break device comprising a closed tubular member formed in two conducting sections inclined to each other and united by insulating material and a partition of conducting material separating the 115 member into two chambers, a movable conducting mass in each chamber, said masses normally closing the circuit through the tubular member when the gun moves regularly in elevation and opening the circuit 120 when the gun moves irregularly in elevation.

5. A circuit-controlling device for electromagnetically actuated firing mechanism for guns comprising circuit-closing means operable to close a circuit at one point when the gun is placed at a predetermined angle, and a circuit make and break device comprising 125

a closed tubular member formed in two conducting sections inclined to each other and united by insulating material, a partition of conducting material separating the member into two chambers, a mass of mercury in each chamber and baffles in the chambers to prevent splashing, said masses normally closing the circuit through the tubular member when the gun moves regularly in eleva-

tion and opening the circuit when the gun moves irregularly in elevation.

In testimony whereof I have signed this specification in the presence of two subscribing witnesses.

EMILE BOURDELLES.
